UNITED STATES PATENT OFFICE.

FRANCIS M. ROBERTSON, OF FULHAM, ENGLAND.

EVAPORATING-PAN.

SPECIFICATION forming part of Letters Patent No. 503,498, dated August 15, 1893.

Application filed April 4, 1892. Serial No. 427,707. (No model.) Patented in Germany February 18, 1893, No. 67,182.

To all whom it may concern:

Be it known that I, FRANCIS MACDONALD ROBERTSON, gentleman, a subject of the Queen of Great Britain, residing at Fulham, in the 5 county of Middlesex, England, have invented new and useful Improvements in Apparatus for Evaporating or Drying, (for which I have obtained Letters Patent in Germany, No. 67,182, dated February 18, 1893,) of which the 10 following is a specification.

My said invention relates to improvements in apparatus for evaporating or drying liquid or semi-liquid materials and is suitable to be employed in the production of salt from brine 15 or sea water, the production of sugar, and in connection with the condenser in distilling, in the manufacture of varnishes and colors, in the treatment of matter such as sewage, and for other uses.

20 In order that the said invention may be more clearly understood and readily carried into effect I will proceed, aided by the accompanying drawings, more fully to describe the same.

25 In the drawings: Figure 1 is an end elevation of an apparatus constructed according to my invention. Fig. 2 is a side elevation thereof. Fig. 3 is a longitudinal section taken on the line 3—3 of Fig. 1. Fig. 4 is an end 30 view of a similar apparatus representing a slight modification. Fig. 5 is a longitudinal section taken on the line 5—5 of Fig. 4. Fig. 6 is a longitudinal section, taken on the line 6—6 of Fig. 7, illustrating a further slight 35 modification; and Fig. 7 is a transverse section taken on the line 7—7 of Fig. 6.

Referring to Figs. 1 to 3, *a* represents a fixed cylindrical chamber which is formed of sheet copper, or other suitable material and 40 which is heated from below by means of any suitable furnace, but I have not thought it necessary to show the latter. This chamber may be surrounded by a steam, oil or water jacket for the purpose of bringing the material 45 under treatment to or maintaining it at the requisite temperature, but as the nature of such jackets is well known, it is not considered necessary to illustrate the same.

The material to be treated is fed into the 50 cylindrical chamber through a suitable feed opening, such as *a'*, by the aid of any suitable conduct, aided if desired, by a screw or

other conveyer, according to the consistency of the material, and the material may be either in a cold state, or it may be previously 55 heated in any suitable manner according to its nature. The material is fed into the cylindrical chamber *a* until the latter is about a quarter full. The feed is then discontinued and a current of air, either in a natural condition or which has been previously dried or heated and which is forced or drawn by any suitable means enters the cylindrical chamber through the feed opening *a'*, and passes continuously through the chamber *a* finding an 60 exit by an exhaust opening *a''*, and, in its course, takes up the fluid or moisture within the cylindrical chamber *a*, as hereinafter more fully described.

Through the center of the cylindrical chamber *a* is passed a shaft *b* which is mounted in bearings *b'* carried by transverse girders *b''* and lubricated by means of oil feeders *b'''*. This shaft *b* is driven by any suitable means such as a driving belt from a steam engine, or 75 other source of power, and upon this shaft *b*, is fixed a continuous screw *b'* the blade of which is hereshown with a plain surface, and the said blade is of such a diameter, as to closely fit the cylindrical chamber *a*. The 80 screw *b'* in the revolution of the shaft *b* constantly passes through the material under treatment, and thus takes up a portion thereof, and, on the continued revolution of the shaft *b*, the material so taken up is exposed to the 85 current of air passing through the cylindrical chamber *a* and the evaporation of the moisture is thus assisted, while, at the same time, the material under treatment is being moved forward.

To permit the return or circulation of the material moved forward by the screw *b'* so that it is kept continuously in motion and caused to circulate from end to end of the cylindrical chamber *a*, until the completion of 95 the process, I employ a device consisting of two tubular conduits *a''* which are located upon the exterior of the cylindrical chamber *a* at each side and at the lower part thereof and communicate by ways *a'''* with the interior of the chamber *a*. By these means the material moved forward by the screw *b'* will 100 be caused to return by the conduits and then forward again, and inasmuch as the tubular

conduits a^3 are placed at or about a level with the bottom of the chamber a no part of the material can escape the action of the screw b' .

In the example given at Figs. 4 and 5 the tubular conduits a^3 are fitted with screw conveyers a^5 the threads of which are formed opposite to that of the screw b' , in order to maintain the circulation of the material under treatment, when through evaporation or otherwise, it is of such a consistency, that it will not readily flow without assistance. After the material has been subjected to the treatment above described for the requisite time to obtain the result desired, it may be removed from the apparatus through a door a^6 provided for that purpose, or by other suitable means. A gage or bevel a^5 is provided at the opposite end of the chamber a to indicate the level of the contents thereof. A blowing or exhausting apparatus is in some cases, employed in connection with either of the openings a' , a^2 , in order to assist the passage from the cylindrical chamber a of the current of air charged with moisture.

In the modification represented at Figs. 6 and 7 the tubular conduits a^3 are dispensed with, and in lieu thereof a cylinder a^8 , the lower part of each end of which is left open, is arranged centrally within the chamber a and within this cylinder a^8 works the screw b' but otherwise the apparatus is similar to that hereinbefore described. In this last described example, the screw b' constantly moves the material forward through the cylinder a^8 while such material returns along the sides and beneath the bottom thereof and re-enters at the opposite end. Apparatus constructed in accordance with the modification lastly described will be found specially suitable for use in distilling operations.

It is of importance that the blade of the screw, fit, as hereinbefore stated, as closely as possible, within the interior of the cylindrical chamber, but so as to be free to revolve therein. The supply of air which is made to pass in at one end of the chamber, escapes at the opposite end thereof as the screw revolves, and in its traverse passes consecutively through the series of spaces above the surface of the material being treated and between the upper or exposed portions of the convolutions of the screw blade. On the revolution of the screw a quantity of the liquid or semi-liquid material under treatment will be thrown upward and outward thereby hermetically closing the space between the outer edge of the screw blade and the interior surface of the cylindrical chamber covering the latter at every revolution of the screw with a thin film of the material. As the current of air travels in a continuous stream through the chamber, it passes over the surface of the material being treated and is brought into contact with any material on the surface of the ever-changing exposed portions of the screw and on the interior surface of the cylindrical chamber and thereby effects the rapid evaporation of

the liquid or moisture at a comparatively low temperature.

By the employment of apparatus, constructed in accordance with this invention in the manner hereinbefore described, I can evaporate water or other liquid freely at a lower temperature than boiling heat and at boiling heat much more rapidly, than by the ordinary methods, the action of the revolving screw being to assist the passage of the current of air through the cylinder and to bring the air during its passage into such intimate contact with the liquid to be evaporated or material to be dried that evaporation takes place with great rapidity, the liquid to be evaporated or the material to be dried being constantly picked up by the blade or blades and thus a largely extended surface for evaporation is secured.

I have hereinbefore referred to the current of air being forced or drawn into and through the cylindrical chamber a , but in places where there is hot and dry atmosphere I allow the screw b' in the course of its revolutions to draw the same through the cylindrical chamber a .

What I claim is—

1. An apparatus for evaporating or drying consisting of a closed chamber provided at one end of its upper part with an inlet and at the opposite end with an outlet, a screw formed by a continuous blade located within such chamber and of such diameter as to fit as closely as possible therein but so as to be free to revolve and means for permitting the return of the material under treatment from the forward end of the chamber back to the initial end, substantially as herein shown and described.

2. The combination of the fixed cylindrical chamber having combined feed and air inlet a' and exhaust opening a^2 the transverse girders b^8 having bearings b^2 , the shaft b provided with a screw conveyer b' and mounted in the bearings, a door through which the material is removed, and a conduit connecting the ends of the cylindrical chamber; substantially as described.

3. The combination of the fixed cylindrical chamber having combined feed and air inlet a' and exhaust opening a^2 the transverse girders b^8 having bearings b^2 , the shaft b provided with a screw conveyer b' and mounted in the bearings, a door through which the material is removed, and a conduit connecting the ends of the cylindrical chamber at the base thereof; substantially as described.

4. The combination of the fixed cylindrical chamber a , having combined feed and air inlet a' , and exhaust opening a^2 , the transverse girders b^8 having bearings b^2 the shaft b provided with a screw conveyer b' and mounted in the bearings, a door through which the material is removed, the two tubular conduits a^3 located upon the exterior of the cylindrical chamber at each side and at the lower part thereof and the ways a^4 connecting the cylin-

drical chamber with the conduits; substantially as described.

5. An evaporator consisting of a fixed cylindrical chamber *a* having combined feed and air inlet *a'* and exhaust opening *a²*, the transverse girders *b³* having bearings *b²*, the shaft *b*, provided with a screw conveyer *b'* and mounted in the bearings, a door through which the material is removed, the two tubular conduits *a³* located upon the exterior of

the cylindrical chamber at each side of the lower part thereof and the ways *a⁴* connecting the cylindrical chamber with the conduits; substantially as described.
